UNITED STATES PATENT OFFICE.

NEIL E. SALSICH, OF BETHLEHEM, PENNSYLVANIA.

RAIL JOINT.

Application filed June 17, 1922. Serial No. 569,178.

To all whom it may concern:

Be it known that I, NEIL E. SALSICH, a citizen of the United States, residing at Bethlehem, Lehigh County, Pennsylvania, 5 have invented certain new and useful Improvements in Rail Joints, of which the following is a specification.

This invention relates to rail joints and particularly to rail joints in which the abutting rail ends are secured together by splice plates welded thereto or secured in position by bolts and by welding.

The heat generated in welding splice plates to rails is intense and frequently is 15 injurious to the rails, when operations are carried out in accordance with the practice now commonly followed. The base flanges of the rail ends are especially susceptible to injury in this manner, the lower welds being made along the lower outer edges of the splice plates which usually lie where the metal of the rail base is thin and easily heated through. As a result of such heating the metal is weakened and the outer 20 margins of the rail bases have frequently broken off under shock and vibration resulting from traffic, so that the entire joint is greatly weakened.

It is desirable to have the splice plates 30 of the self centering type, that is, to have them so designed and constructed that they arrange themselves with their webs substantially parallel to the webs of the rails when the plates are initially drawn into position 35 by the tightening bolts. In order to fulfill this requirement the plates are formed with top and bottom bearing surfaces for abutment against the lower and upper surfaces of the heads and bases of the rails respectively, these surfaces constituting guide 40 surfaces for the purpose mentioned.

In accordance with the present invention the splice plates are formed with the desired bearing or guide surfaces so that they may 45 be quickly and accurately assembled with the rails and at the same time, are so designed that their outer lower longitudinal edges which are adapted to be welded to the rail bases, are displaced inwardly relatively to the bearing surfaces so as to be as close as possible to the webs of the rails to the end that the lower weld may be formed where the metal of the rail base is comparatively thick and not liable to be injured by the heat incident to the welding operation. It will be understood, of course,

that the bases of the rails with which the plates are to be used decrease in thickness in each direction from the webs toward the outer edges.

In the accompanying drawings one form of splice plate is illustrated which fulfills the requirements above mentioned, and in the following description the construction of the plate will be described in detail. It 65 will be understood, however, that the exact form of the plate may be changed when the same is intended for different forms of rails and that various minor modifications are contemplated.

In the drawings:

Fig. 1 is a side elevation of the abutting ends of two girder rails showing the plate in position; and

Fig. 2 is a section on line 2—2 of Fig. 1, 75 a portion of one plate being broken away.

The rails R are of the girder type each having a head 10, a web 11 and a base 12, the lower surfaces of the head 13 and 14 being downwardly and inwardly inclined and 80 the upper surfaces 15 and 16 of the base 12 being upwardly and inwardly inclined. The splice plates are indicated at S and although of different heights are formed in the same manner. Each splice plate comprises a web 17 having transverse flanges 18 at its ends. The upper and lower edge surfaces of the web converge inwardly to fit closely against the corresponding inwardly converging surfaces of the head and base 90 and the same is true of the end flanges 18, the upper and lower surfaces of these flanges being so inclined as to fit closely against the inwardly converging and oppositely facing surfaces of the rail head and 95 base.

In applying the plates to the rail ends, bolts B are passed through registering apertures in the plates and webs 11 of the rails and are gradually tightened to draw the 100 plates toward the webs of the rails so that their inclined upper and lower surfaces bear tightly against the corresponding surfaces of the heads and bases of the rails. When the plates have been drawn into position in this manner welding material is applied as at 19 along the lower edge of the plates and as at 20 along their upper edges so that the plates are rigidly secured in position.

It will be seen that by the use of the end flanges 18 the plates are provided with up-

per and lower guide surfaces of sufficient length transversely of the plate to prevent any tendency which the plate may have to tilt as it is drawn into position by the 5 bolts, so that their webs 17 do not lie parallel to the webs 11 of the rail. Furthermore that those edges of the plate which are to be welded to the bases of the rails are disposed at a considerable distance from the 10 edges of the rails. In this manner both theoretical requirements are realized and it will be seen that the rail joint formed will be of a strong nature as well as being comparatively inexpensive, the plates employed 15 being of relatively light weight and easy to fabricate.

Having thus described the invention, what I claim as new and desire to secure by Letters Patent is:

20 1. A splice plate for a rail joint having a lower outer edge adapted to be positioned adjacent the base of a rail and to be welded thereto, and also having a portion extending outwardly beyond said lower edge which portion is provided with upper and lower guide surfaces adapted to bear respectively against the heads and bases of the abutting rail ends.

2. A splice plate for a rail joint the outer 30 lower edge of which is adapted to be positioned adjacent the base of a rail and to be welded thereto, and having a plurality of portions extending outwardly beyond said lower edge which portions are provided with upper and lower guide surfaces adapted to bear respectively against the heads and bases of the abutting rail ends.

3. A splice plate for a rail joint having a lower outer edge adapted to be positioned 40 against the base of a rail and to be welded thereto, and also having a portion at each end extending outwardly at an angle to the main portion of the plate beyond said lower edge, which flanges are provided with upper and lower guide surfaces adapted to bear respectively against the heads and bases of the abutting rail ends.

4. A splice plate for a rail joint having a lower outer edge adapted to be positioned 50 against the base of a rail and to be welded thereto, and also having a flange at each end extending outwardly at an angle to the

main portion of the plate beyond said lower edge which portion is provided with inclined upper and lower guide surfaces 55 adapted to bear respectively against the heads and bases of the abutting rail ends.

5. A rail point comprising in combination with the abutting ends of two girder rails, spliced plates on opposite sides of the 60 rails and overlapping the rail ends, each splice plate having a lower outer edge adjacent the rail base and adapted to be welded thereto and also having a portion extending outwardly beyond said lower edge which 65 portion is provided with upper and lower guide surfaces adapted to bear respectively against the heads and bases of the abutting rail ends.

6. A rail joint comprising in combination 70 with the abutting ends of two girder rails, splice plates on opposite sides of the rails and overlapping the rail ends, each splice plate having a lower outer edge adjacent the rail base and adapted to be welded 75 thereto and also having a flange at each end extending outwardly at an angle to the main portion of the plate beyond said lower edge, which portion is provided with inclined upper and lower guide surfaces 80 adapted to bear respectively against the heads and bases of the abutting rail ends.

7. A splice plate for a rail joint having a lower outer edge adapted to be positioned adjacent the base of a rail and to be welded 85 thereto, a portion of the plate extending outwardly beyond said lower edge and provided with a guide surface adapted to bear against the base of a rail, and the upper edge surface of the plate comprising a 90 guide surface adapted to bear against the lower surface of a rail head.

8. A self centering splice plate for a rail joint having upper and lower guide surfaces adapted to bear against the heads and bases 95 respectively of abutting rail ends, with the lower outer edge adjacent the bases of the rails and in position to be welded thereto, and a portion extending outwardly beyond said lower outer edge and designed to engage a rail base.

In testimony whereof I hereunto affix my signature.

NEIL E. SALSICH.
